STRAND WINDING DEVICE

John H. Garrott, Bloomfield, N. J., assignor to
The Clark Thread Company, Newark, N. J., a
corporation of New Jersey

Application October 23, 1941, Serial No. 416,193

6 Claims. (Cl. 242—43)

This invention is an improvement in the art of strand winding on bobbins.

It is desirable that the strand mass at the end of the bobbin opposite the base be such as to facilitate the withdrawal of the thread from the bobbin in use and various mechanisms have been described in patents to produce bobbins wherein the mass of thread has a tapered end.

It is an object of the present invention to provide improved mechanism to produce a tapered end. It is a further object to provide mechanism by means of which the contour of the generally tapered end can be varied conveniently and efficiently.

The invention is capable of application to conventional strand winding machines. In such machines the bobbin may be rotatably mounted on an arbor driven by suitable driving mechanism. A thread guide is mounted upon suitable traverse mechanism in such a way that the thread guide reciprocates through a predetermined path axially of the bobbin and also moves radially thereof, the thread guide bearing against the surface of the strand mass and being radially moved by the building up of said mass radially of the bobbin. Such conventional mechanism is well known and need not be described except to the extent necessary to show the manner in which the present invention cooperates therewith.

In accordance with the invention, pivoted means, as, for example, a lever, is mounted to swing horizontally. There is a connection between one end of the lever and a bobbin-urging sleeve mounted on the arbor adapted to convert swinging movement of the lever into axial movement of the bobbin. There is also provided means, preferably of a resilient nature, connected to the lever tending to urge it to swing horizontally and therefore to impart an axial movement to the bobbin. A cam follower may be mounted on said lever. There is also provided a cam mounted to rotate about an axis parallel to the axis of the mandrel. For example, this cam may be mounted to rotate upon a fixed shaft or arbor in suitable spaced relation to the bobbin-carrying arbor and having an axis parallel thereto, and this cam-carrying arbor as well as the lever pivoted to swing horizontally may be carried by a single bracket secured to the framework of the winding machine. This rotatably mounted cam is provided with an eccentric surface which engages the lever, as for example by means of the cam follower on the lever, and opposes the swinging movement of said lever. By rotating this cam, the lever is permitted to follow the

eccentricity of the cam surface and axial movement is thereby imparted to the bobbin in accordance with the character of that eccentric surface. As a result, the contour of the strand mass on the bobbin at the end thereof opposite the base will be of the same character as the contour of the cam. That contour may be varied through quite a wide range. If the contour of the cam is projected on a horizontal plane from the cam in its operative position, that projection may be a straight line inclined in relation to the axis of the bobbin, or a curved line concave or convex in relation to the axis of the bobbin, or it may have any desired configuration, irregular or otherwise.

One of the desired configurations is that of a series of steps so that the end of the bobbin may be given a so-called "stepped wind." The rotation of the cam is effected by the swinging radial movement of the traverse mechanism. For example, the rotatably mounted cam may be driven by a gear engaging a rack pivotally mounted on the traverse mechanism or by any other suitable means.

The invention will be defined in the claims and will be further described and illustrated in respect of a specific embodiment of the principles thereof in the following description and illustrated by the drawings, in which:

Fig. 1 shows an end view of a conventional winding machine equipped with the improvement of the present invention;

Fig. 2 is a top plan view of the same, showing the position of the parts at the beginning of the winding operation;

Fig. 3 is a horizontal plan view, partly in section, on the line 3—3 of Fig. 1 showing the relation of certain parts after completion of the winding operation wherein a "stepped wind" is shown as imparted to the strand mass on the bobbin by way of illustration;

Fig. 4 is a side elevational view, partly in section;

Fig. 5 is a fragmentary view, partly in section, showing the rotatably mounted cam and its eccentric surface, which in this case has a configuration adapted to produce a "stepped wind";

Fig. 6 is a view taken on the line 6—6 of Fig. 5 to further illustrate the cam and the engagement of the eccentric surface thereof with the cam follower on the lever mounted for horizontal swinging movement;

Fig. 7 is a further view looking in the direction of the arrows at the left of Figs. 1 and 2 and in the same direction as the view shown in Fig. 5 to further illustrate the mounting of the rotatably

mounted cam and its immediately associated mechanism and also illustrating the single bracket which may be employed to support the cam and lever;

Fig. 8 is a view taken on the line 8—8 of Fig. 7;

Fig. 9 is an enlarged fragmentary view, partly in section, of a part of the traverse mechanism, showing the thread guide bearing against the strand mass and presenting the thread to said mass;

Fig. 10 shows one species of the eccentric surface on the cam adapted to produce a scalloped wind illustrated in Fig. 10a;

Fig. 10a shows a scalloped wind produced by a cam 61 having the contour 61A shown in Fig. 10;

Fig. 11 shows a species of eccentric contour on the cam which is convex in relation to the axis of the bobbin and is adapted to produce a convex contour of the strand mass at the end thereof, as illustrated in Fig. 11a;

Fig. 11a shows a convex tapered wind produced by a cam 62 having the contour 62A shown in Fig. 11;

Fig. 12 shows a straight line taper characterizing the cam surface adapted to produce a straight line taper on the strand mass, as illustrated in Fig. 12a.

Fig. 12a shows a straight-line tapered wind produced by a cam 63 having the contour 63A shown in Fig. 12.

Figs. 10, 11, and 12 are projections on a horizontal plane of the contour of the eccentric cam surface, these projections being taken from the cam in its operative position onto said horizontal plane.

Referring to the drawings more in detail, in which like parts are represented by the same numerals, a bobbin 1 is mounted on an arbor 2 driven through clutch mechanism 3 by a drive shaft 4 driven in a conventional manner by mechanism not shown. For the sake of convenience, the mechanism which presents the thread to the bobbin and the strand mass will be referred to generally as traverse mechanism 5 which it is not necessary to show or describe in detail because, except for the modification of the structure thereof for cooperation with the structure of the present invention, such traverse mechanism is well known. The traverse framework 6 carrying the traverse mechanism 5 is pivoted to move radially in relation to the axis of the arbor 1 by means of the shaft 7 journaled in bearings 8 in framework 6A in the machine, the conventional counterweight being provided for this purpose. The traverse mechanism includes the traverse bar 10 connected to the shoe 11 which is given a reciprocating motion on the rail 12 by a grooved eccentric wheel 14 mounted on the shaft 7. The traverse bar 10 carries the member 16 on which the thread guide 18 is mounted and through which the thread is passed and presented to the strand mass 20 for winding after passing over the thread guide roller 22.

A bracket 23 is adjustably secured to the bars 24, 24A of the framework of the machine by means of clamps 25 and bolts 26 secured by nuts 27. An extension of this bracket 23 is provided with a bearing or pivot 28 in which is journaled the vertical arm 29 of an elbow member 30 connected at one end to the bar 24 by the spring 32. On this arm 29 is secured, by means of a set screw 34, a lever 36 mounted to swing horizontally and provided at one end thereof with a member 38 which rides in a groove defined by

the flanges 40 of a sleeve 41 slidably mounted on arbor 2. Since the bobbin 1 is mounted to slide axially on the arbor 2, the lever 36 acting under the bias of the spring 32 tends to move the bobbin 1 axially along said arbor 2 and to thereby move the bobbin 1. The lever 36 carries a cam follower 45 or its equivalent which may take the form of a pin adjustably mounted on the lever in the slot 47 by means of a nut 49 engaging the threaded end 50 of said pin so that the said pin or cam follower 45 may be adjusted longitudinally of the lever 36.

An extension of the bracket 23 carries a slotted member 52 in which the arbor 54 having a threaded end 55 is adjustably secured by means of a nut 56 so that the arbor 54 can be horizontally adjusted in relation to the cam follower 45 for a reason to be presently explained. On this arbor 54, there is rotatably mounted a cam element 60 illustrated in detail in Figs. 5 and 6. This cam element 60 has an eccentric surface 61, the character of which is subject to considerable variation. In the specific form shown in Figs. 5 and 6, the contour of this eccentric surface has a stepped character and, if this contour is projected from the cam in its operative position onto a horizontal plane (see for example Figs. 2 and 3), the result is an irregular line of a stepped character. The eccentric surface 61 of the cam 60 bears against the cam follower 45 and thus opposes the tendency of the horizontal lever 36 to swing in its horizontal plane and therefore also opposes the tendency of said lever 36 to give the sleeve 41 and bobbin 1 an axial thrust. Suitable rotation of this cam 60 permits the cam follower 45 and lever 36 to follow the eccentricity of the cam surface and thus to cause the lever 36 to move the bobbin 1 axially in accordance with the character of the cam surface. If the projection of the cam contour on a horizontal plane is a straight line inclined in relation to the axis of the mandrel (see Fig. 12), rotation of the cam in a clockwise direction at a uniform rate will produce a uniform rate of axial movement in the bobbin and the result will be the production of a straight taper on the strand mass at the end thereof opposite the base of the bobbin (see Fig. 12a). A differential rate of axial movement of the mandrel and bobbin may be, however, produced by choosing appropriate cam surfaces, as illustrated in Figs. 10 and 11.

Fig. 10 illustrates an eccentric cam surface 61A of a scalloped character and Fig. 11 an eccentric cam surface 62A convex in relation to the axis of the arbor 2. Fig. 10a illustrates the scalloped wind obtained from an eccentric cam surface of the character shown in Fig. 10, and Fig. 11a shows a convex wind obtained from a cam surface of the character shown in Fig. 11. Fig. 12 shows a straight-line cam surface contour 63A adapted to produce the straight-line wind illustrated in Fig. 12a. Figs. 5 and 6 show in detail the type of cam surface adapted to produce a stepped wind of the character shown in Fig. 3 and as already explained.

Rotation of the cam is effected, as shown, in consonance with the axial movement of the traverse mechanism 5. For this purpose, a gear 64 is secured to the cam 60 and rotatably mounted on the arbor by means of the hub 66 secured to the cam 60 and one or more keys or dowel pins 68. The gear 64 is engaged by a rack 70 pivotally secured to the traverse frame 6 by means of the pin 72. A roller 74 bears against the top of the rack 70, the roller 74 being rotatably mounted

on a pin 75 carried by the bracket 16. This bracket is split at one end and secured to the arbor by means of the screw 18. The upper end of the bracket is provided with a slot 80 in which the pin 75 is adjustably mounted by means of a nut 81. The purpose of this adjustable roller mounting is to permit the use of gears of varying size so as to control the rate of movement of the cam and thereby control the degree of taper in the end of the strand mass.

The fraction of the circumference of the cam occupied by the eccentric surface thereof may be varied through a wide range and, as already stated, the particular character of the contour of the eccentric surface may also be varied.

In order to permit the cam follower to properly engage with and follow the eccentricity of the cam surface, it is desirable to be able to adjust the cam carrying arbor 54 and the cam follower 45 in relation to each other and for this purpose provision is made so that this relative adjustment may readily be obtained. It is for this purpose that a slot 84 in the bracket 23 is provided so that the cam-carrying arbor can be given a laterally adjusted position. For the same purpose the slot 47 is provided in the lever to permit complementary or corresponding lateral adjustment of the cam follower. Furthermore, with any given cam the latter may be angularly adjusted on the arbor by providing a series of keyways in the hub to receive dowel pins securing the hub to the gear.

The bracket 23 carrying the lever and cam may desirably be formed of a single casting.

In operation, the bobbin 1 is rotated and thread is fed thereto through the guide 18 which is given a reciprocating movement in a predetermined and fixed path parallel to the axis of the bobbin by the traverse mechanism 5. As the strand mass 20 builds up on the bobbin the traverse mechanism 5 and frame 6 is given a radial movement in relation to the axis of the bobbin and the frame 6 swings in a plane perpendicular to the axis of the bobbin. The rack 10 pivoted to the frame 6 and engaging the gear 64 causes rotation of the cam 60. The lever 36 tends to urge the bobbin 1 axially along the arbor 2, this tendency being opposed by engagement of the eccentric cam surface with the cam follower 45 carried by the lever. Rotation of the cam 60 by the rack 10 permits the lever to follow the eccentricity of the cam surface and axial movement is therefore imparted to the bobbin in accordance with the character or contour of the eccentricity of the cam surface. Since the "throw" or path through which the thread guide reciprocates axially of the bobbin is fixed and is independent of the axial movement of the bobbin, the character or contour of the strand mass at the end of the bobbin opposite the base thereof is of the same character as the contour of the cam, by virtue of the character of the cam, its rotation in the stated manner and its cooperation with the means tending to urge the bobbin axially along the arbor on which the bobbin is mounted.

I claim:

1. In a machine, for winding a strand mass on a bobbin, of the type wherein traverse mechanism carrying a thread guide moves axially and radially in relation to a bobbin mounted to rotate with and move axially along a horizontal revolvably mounted arbor; pivoted means mounted to swing horizontally and provided with means tending to urge said bobbin axially along said arbor; a cam mounted to rotate about an axis parallel to the

axis of the bobbin, said cam having an eccentric periphery which, in projection, from its operative position, on a horizontal plane, has a contour of substantially the same character as the contour of the taper of the end of the strand mass to be wound on said bobbin; a cam follower on pivoted means; said eccentric cam periphery engaging said cam follower and opposing swinging movement of said pivoted means; and means actuated by the radial movement of said traverse mechanism to rotate said cam and thereby permit said pivoted means to follow said eccentric periphery and to impart axial movement to the bobbin in accordance with the character of said eccentric periphery.

2. In a machine, for winding a strand mass on a bobbin, of the type wherein traverse mechanism carrying a thread guide moves axially and radially in relation to a bobbin mounted to rotate with and move axially along a revolvably mounted arbor; a lever pivoted intermediate the ends thereof to swing horizontally; means at one end of the lever adapted to convert swinging movement of the lever into axial movement of the bobbin; resilient means connected to the other end of the lever normally urging the lever to swing and thereby cause axial movement of the bobbin; a cam mounted to rotate about an axis parallel to the axis of the bobbin, said cam having an eccentric periphery which, in projection, from its operative position, on a horizontal plane, has a contour of substantially the same character as the contour of the taper of the end of the strand mass to be wound on said bobbin; a cam follower on said lever; said eccentric cam periphery engaging said cam follower and opposing swinging movement of said pivoted means; and means actuated by the radial movement of said traverse mechanism to rotate said cam and thereby permit said lever to follow said eccentric periphery and to impart axial movement to the bobbin in accordance with the character of said eccentric periphery.

3. In a machine, for winding a strand mass on a bobbin, of the type wherein traverse mechanism carrying a thread guide moves axially and radially in relation to a bobbin mounted to rotate with and move axially along a revolvably mounted arbor; pivoted means mounted to swing horizontally and provided with means tending to urge said bobbin axially along said arbor; a cam mounted to rotate about an axis parallel to the axis of the mandrel, said cam having an eccentric periphery which, in projection, from its operative position, on a horizontal plane, has a contour of substantially the same character as the contour of the taper of the end of the strand mass to be wound on said bobbin; a cam follower on said pivoted means; said eccentric cam periphery engaging said cam follower and opposing swinging movement of said pivoted means; a gear adapted to rotate said cam; and a rack engaging said gear and actuated by the radial movement of said traverse mechanism to rotate said gear and cam and thereby permit said lever to impart axial movement to the bobbin in accordance with the character of the eccentric periphery of said cam.

4. In a machine, for winding a strand mass on a bobbin, of the type wherein traverse mechanism carrying a thread guide moves axially and radially in relation to a bobbin mounted to rotate with and move axially along a revolvably mounted arbor; a bracket secured to the framework of said winding machine; a lever pivoted on said

bracket to swing horizontally; means at one end of said lever to convert swinging movement of the lever into axial movement of the bobbin; resilient means normally urging said lever to swing horizontally about its pivot; a horizontally mounted stationary arbor carried by said bracket and having an axis parallel to the axis of the bobbin; a cam rotatably mounted on said arbor; a cam follower on said lever; said cam having an eccentric surface engaging said cam follower and opposing swinging movement of said lever; means on said bracket and lever to permit relative adjustment of said cam follower in relation to said cam surface; and means actuated by the radial movement of said traverse mechanism to rotate said cam and thereby permit said lever to follow said eccentric cam surface and to impart axial movement to the bobbin in accordance with the character of said eccentric periphery.

5. In a machine, for winding a strand mass on a bobbin, of the type wherein traverse mechanism carrying a thread guide moves axially and radially in relation to a bobbin mounted to rotate with and move axially along a revolvably mounted arbor; a lever mounted to swing horizontally and provided with means tending to urge said mandrel and bobbin axially along said shaft; a cam follower mounted on said pivoted means; a cam mounted to rotate about an axis parallel to the axis of the bobbin, said cam having an eccentric surface engaging said cam follower

and opposing the swinging movement of said lever; and means actuated by the radial movement of said traverse mechanism to rotate said cam and thereby to permit said cam follower and lever to follow the eccentricity of said cam surface and thereby to impart axial movement to the bobbin in accordance with the character of said eccentric cam surface.

6. In a machine for winding a strand mass 10 on a bobbin, of the type wherein traverse mechanism carrying a thread guide moves axially and radially in relation to a bobbin mounted to rotate with and move axially along a horizontal revolvably mounted arbor; bobbin-urging means 15 tending to urge said bobbin axially along said arbor; a cam mounted to rotate about an axis parallel to the axis of the bobbin, said cam having an eccentric periphery which, in projection, from its operative position, on a horizontal 20 plane, has a contour of substantially the same character as the contour of the taper of the end of the strand mass to be wound on said bobbin; said eccentric cam periphery engaging said bobbin-urging means and opposing said axial movement of the bobbin; and means actuated 25 by the radial movement of said traverse mechanism to rotate said cam and thereby permit said bobbin-urging means to follow said eccentric periphery and to impart axial movement to the bobbin in accordance with the character of said eccentric periphery.

JOHN H. GARROTT.
